HERMAN E. HEINE, OF MILWAUKEE, WISCONSIN, ASSIGNOR TO BRADLEY WASHFOUNTAIN COMPANY, OF MILWAUKEE, WISCONSIN, A CORPORATION OF WISCONSIN

WASH-FOUNTAIN SPRAY HEAD

Application filed September 27, 1926. Serial No. 138,078.

This invention relates to improvements in washfountain spray heads.

Heretofore, heads for washfountains have been so constructed that a plurality of closely allied streams of water are thrown from the head.

The present invention, however, has for its object the provision of a spray head which will discharge a sheet or curtain of water instead of the individual streams, as heretofore.

A further object of the invention is to provide a washfountain spray head which is of simple construction, is strong and durable, is efficient in operation, and is well adapted for the purpose described.

With the above and other objects in view, the invention consists of the improved washfountain spray head and its parts and combinations as set forth in the claim and all equivalents thereof.

In the accompanying drawing in which the same reference characters indicate the same parts in all of the views:

25 Fig. 1 is a side view partly in vertical section of the improved spray head;

Fig. 2 is an enlarged fragmentary detail view thereof, partly in section; and

30 Fig. 3 is a fragmentary diagrammatic plan view showing the nature of the sheet of water discharged from the spray head.

Referring now more particularly to the drawings, it will appear that the numeral 8 indicates a spray head casing which is preferably of curved form in horizontal plane. The casing is provided with an inlet opening 9, communicating with an interior chamber 10 into which water is admitted by means of a valve 11 to be discharged by the spray head.

40 The outer periphery of the spray head is provided with a curved line of radial outwardly and downwardly directed spray apertures 12 through which water is discharged for washing purposes. The exterior 45 of the head is provided with a groove 13 connecting all of said spray apertures.

Heretofore, in spray heads constructed with the spray apertures unconnected, the result has been a discharge of a plurality of minute streams. However, the present de-

vice, by means of the slot connection between all of the spray apertures, discharges a sheet or curtain of water. So far as can be determined, the physical cause of this action is that the proximity of the apertures in the spray head and the horizontal connecting groove causes the water when leaving the apertures to spread. The spreading of the water, in combination with the surface pressure peculiar to water when released, causes the water to combine in a solid circumferential sheet. The advantages of the discharge of a sheet of water or curtain, over a solid stream as discharged from a faucet is the economy of water consumption, and the convenience to the user.

From the foregoing description, it will be seen that the improved spray head is of very simple and novel construction, and is well adapted for the purposes described.

What I claim as my invention is:

A spray head, consisting of a casing of curved form in horizontal plane and formed with a curved line of outwardly and downwardly directed spray apertures, said casing also having an exterior elongated groove intersecting all of said apertures, said groove being of less width than the diameter of a spray aperture and materially of less depth than the axial extent of said aperture whereby the discharge assumes the form of a continuous sheet of water and being adapted to discharge a sheet of water downwardly and outwardly therefrom.

In testimony whereof, I affix my signature.

HERMAN E. HEINE.
